UNITED STATES PATENT OFFICE.

WEEDEN B. UNDERWOOD, OF ROCHESTER, NEW YORK, ASSIGNOR TO WILMOT CASTLE COMPANY, OF ROCHESTER, NEW YORK, A CORPORATION.

ELECTRIC HEATER.

1,215,748.

Specification of Letters Patent. Patented Feb. 13, 1917.

Application filed December 14, 1915. Serial No. 66,821.

To all whom it may concern:

Be it known that I, WEEDEN B. UNDERWOOD, a citizen of the United States, and resident of Rochester, in the county of Monroe and State of New York, have invented 5 certain new and useful Improvements in Electric Heaters, of which the following is a specification.

This invention relates to electrical devices 10 for heating water, or other fluids.

The object of the invention is to produce an electric heater of a compact, durable and efficient form, and particularly one in which the heating-units may be subjected to a substantial mechanical pressure, whereby their parts are brought into close contact with each other and with the walls of the chambers in which the fluid to be heated is contained, thus promoting the rapid conduction 15 of the heat, and at the same time preventing the attainment of an excessive temperature by the heating-elements.

To the foregoing end the invention involves various novel features of construction 20 and arrangement hereinafter set forth:

In the accompanying drawings:

Figure 1 is a vertical median section of an electric heater embodying the present invention;

Fig. 2 is a front-elevation, with parts broken away to show the interior construction;

Fig. 3 is an enlarged detail-view, showing the core and the heating-elements of one of the heating-units;

Fig. 4 is a cross-section of parts of one of the heating-units; and

Fig. 5 is a cross-section of a complete heating-unit.

The invention is illustrated as embodied in a heater comprising three castings or body-members 18, 19 and 20. The members 18 and 19 have inner walls 21 and 22, and outer walls 23 and 24, respectively, the 45 spaces 26 between these walls being adapted for the reception of the water which is to be heated. The intermediate member 20 is formed with a similar water-space, and all of these spaces are connected, at top and bottom, by passages 27 and 28, as shown particularly in Fig. 1, the passage 27 communicating with an inlet-pipe 29 for cold water, while the passage 28 communicates with an outlet-pipe 30 for the heated water, these pipes being threaded into the front

body-member 18. Gaskets 31 are interposed between the adjacent surfaces of the body-members, around the openings forming the passages 27 and 28, to prevent leakage of water at these points, and the body-members are all tightly clamped together by means of through-bolts 32.

The heating-units H, which are of the usual flat, elongated form, are interposed between the adjacent surfaces of the body-members, the surfaces of the intermediate member 20 being recessed, as shown in Fig. 1, to receive the units. This construction is such that when the parts are drawn together by the bolts 32 the heating-units are tightly clamped between the adjacent surfaces, so that the heat from them is effectively conducted through the walls of the body-members, and thus directly to the water inclosed between these walls. The 75 heated water rises between the walls and escapes through the passage 28 and the pipe 30, being replaced by cold water flowing into the pipe 29.

I have devised a form of heating-unit which is particularly adapted to sustain the pressure above referred to without injury. For this purpose I employ, as shown particularly in Figs. 3 and 4, a central core in the form of a thick strip 10 of mica, or other refractory material, the strip being provided with notches on its longitudinal edges. In place of a single resistance-device or heating-element, I employ two such devices, in the form of narrow strips 11 and 12 of resistance metal. Each of these strips is wound in a modified helix upon the core 10, all of the stretches of the strip 11 being normal to the length of the core on the front of the core, as shown in Fig. 3, while on the back of the core the stretches of the strip 11 are inclined to the length of the core, this disposition being secured by the use of the proper notches in winding the strip. The strip 12, on the other hand, is wound so that its stretches on the rear surface of the core are normal to the length thereof, and its stretches on the front of the core are inclined in the same direction as the rear stretches of the strip 11. From this disposition of the parts it results that the stretches are arranged exactly opposite each other on the two sides of the core. Accordingly, when the parts are subjected to pressure this pressure is transmitted directly through the core 110

from strip to strip, and there is no tendency, therefore, to bend or shear the core, such as would occur in the case of the usual helical arrangement of the heating-element.

5 Another feature of the invention resides in the means for connecting the heating-elements with the external source of current. For this purpose I employ, as is usual, a flat conductive ribbon 13, but in accordance with 10 the present invention the core is provided with a perforation 14, at some distance from its end, and the strip 13 is passed through this perforation and then bent back on both sides of the core. Its two portions may lie 15 either inside or outside of the heating-elements, but in either case it makes contact with several turns of them on both sides of the core, and at the same time its location in the perforation 14 prevents it from being 20 displaced in any direction relatively to the core or the heating-elements.

The heating-unit is completed by applying a sheet of insulating material 16 to either 25 side of the parts shown in Fig. 3, and then enveloping the whole in flexible sheet-metal 17, as shown in Fig. 5.

The terminal-conductors 13 are attached to binding-posts 34, which are mounted on a 30 yoke 33 supported by lugs projecting from the body-members, as shown in Fig. 2.

Whenever it becomes necessary to replace or repair one of the heating-units, this may 35 very readily be done upon removing the bolts 32, whereupon the body-members may be taken apart and either of the units removed and replaced.

While the heater has been shown and described as comprising three body-members, it will be apparent that the number may be indefinitely increased without any change in 40 the general form or construction of these members, thus providing a heater of any desired capacity; and in general, the invention is not limited to the embodiment thereof hereinbefore described and illustrated in the 45 accompanying drawings, but may be embodied in various other forms, within the nature of the invention as it is defined in the following claims.

I claim:

1. An electric heater comprising a plurality of separate hollow bodies each having a chamber and openings at opposite ends of the chamber, said openings providing two continuous passageways at the ends of the 55 heater, the two passages being connected by the chambers, and electrical heating units interposed between the hollow bodies at points between the two passageways.

2. An electric heater comprising a plurality of separate hollow bodies lying in abutting relation and formed with chambers between them, each body having an internal chamber and openings at opposite ends of the chamber, said openings providing two 60 continuous passageways at the ends of the heater, the two passageways being connected by the internal chambers, and electric heating units interposed in the chambers between the hollow bodies.

WEEDEN B. UNDERWOOD.
